SHOE COUNTER

Charles A. Thurston, Haverhill, Mass., assignor to John W. Herlihy, William W. Herlihy, and John J. Herlihy, all of Haverhill, Mass., doing business as Lowell Counter Company, Lowell, Mass.

Application August 2, 1935, Serial No. 34,410

6 Claims. (Cl. 36—68)

This invention relates to certain improvements in stiffeners for the heel portions of shoes, usually termed "counters", and which are usually made either of very stiff leather board or leather and, when molded, have a flange on the bottom edge which extends onto the heel seat.

In the manufacture of many types of shoes, when the shoe is lasted the edge portion of the upper is drawn over onto the flange of the counter and secured in position by tacks which are driven through the flange into the heel part of the innersole, or heel stiffener, thereby forming the heel seat. It is, of course, desirable that the heel seat be as level as possible, so that, when the heel is attached, it will rest firmly thereon at all points about the sides and back of the shoe at the edge. To secure a level heel seat, it is usually subjected to considerable pounding and is often "ironed". Much difficulty is often encountered in securing a perfectly level heel seat for several reasons:—partly on account of the wrinkles or folds in the upper leather at the back of the shoe, and principally on account of the heads of the tacks employed to secure the upper in position, which are liable to protrude above the level of the heel seat, so that the heel is prevented from resting thereon at all points.

Prior to my invention, various attempts have been made to obviate this difficulty, none of which, so far as I am aware, have been entirely successful, or satisfactory.

The object of my invention is to provide a form of counter which is so constructed, or shaped that the folds of the upper leather, and the heads of the tacks which are liable to protrude above the level of the heel seat, may be readily depressed below the level thereof, so that a heel seat which is perfectly level may be secured without difficulty and the heel, when placed thereon, will engage at all points about its edge.

I accomplish this object by so molding the counter that a rib is formed on the top or inner side of the flange thereof close to the inner surface of the sides and back of the counter, said rib being extended entirely about the heel seat portion of the counter, so that when the counter is placed on the last, the rib will support the flange portion, which projects beyond it, out of contact with the heel part which is directly engaged by the rib.

Consequently, when the edge portion of the upper is tacked down onto the heel seat, the tacks will be driven into the counter flange within the rib and the flange will be bent down into contact with the heel part, so that the heads of

the tacks and folds of the leather may be depressed below the level of the edge of the heel seat and will not interfere with the subsequent seating of the heel thereon.

For a more complete disclosure of the invention reference is now made to the following specification in connection with the accompanying drawing, in which:

Fig. 1 is a perspective view of a shoe counter embodying my invention.

Fig. 2 is a sectional view thereof at line 2—2 of Fig. 1.

Figs. 3 and 4 are cross sectional views of the heel portion of a last having a partly finished shoe thereon, in which a counter embodying my invention is employed.

Fig. 5 is a detail sectional view on an enlarged scale at line 5—5 of Fig. 1.

In the drawing *a* indicates a common type of counter having side portions *b* which, in the present instance, are of sufficient length to extend for a short distance beyond the breast line of the heel, and a bottom flange *c*, which is skived to a sharp edge, as is customary.

According to my invention I form an integral rib *d* on the top or inner side of the flange *c*, which extends continuously entirely about the side and back portions of the counter and terminates approximately at the point where the breast line is normally located. That is, there is no object in having the rib extend beyond the breast line, although it is desirable to have it extend nearly or quite to the breast line, as will hereafter appear. The rib *d* is approximately semi-cylindrical in cross section, and is formed at the time of the molding operation of the counter by forming a correspondingly shaped groove in the face side of the plug, over which the counter is molded in an ordinary counter molding machine, so that, when the flange is wiped in over the face of the plug, and is, at that time, subjected to a heavy pressure, the material, which is then in temper, will be forced into the groove, completely filling the same, so that a correspondingly shaped rib will be formed on the inner side of the flange, the bottom side being formed flat, as is customary.

As illustrated in Fig. 3, when the counter is inserted between the lining *e* and upper *f* of the shoe and placed on the last *g*, on which an inner sole, or heel and shank-stiffener *h* has been placed, the rib *d* will bear directly on the heel part and will support the flange *c* above the level of the surface thereof, so that there will be an open space therebetween. The upper, which has been

lasted in onto the flange, will then be secured in position by tacks *i*, which will be driven thru the flange beyond or within the rib *d* and into the heel part, so that the flange portion which projects beyond the rib will be bent down onto the heel part, thereby permitting the tacks to be driven in to such an extent that their heads will be depressed well below the level of the edge of the heel seat, as indicated in Fig. 4. All folds or wrinkles in the leather will also be pressed below the level of the surface on which the heel is to be seated.

Consequently, when the heel is placed in position on its seat, it will bear uniformly thereon at 15 all points.

As the rib *d* is formed at the time the molding operation is performed, it will be apparent that, after the groove has been formed in the plug of the molding machine, counters provided with a 20 rib on the inner or the upper sides of the flange, as described, may be produced without extra expense, as compared with any other ordinary type of counter.

The transversely convex form of rib shown is 25 preferable, principally on account of the fact that the concave form of groove in the plug which forms the rib will not interfere with the ready removal of the counter from the molding machine, while other forms of grooves might tend 30 to prevent removal. While the rib is located close to the sides of the counter, a space is provided therebetween on account of the convex formation of the rib which permits the counter to yield slightly to the pressure of the edge of the 35 heel when it is attached, so that a perfect joint will be made between the extreme outer edge of the heel and the heel seat.

As shown in Fig. 5, while the greater portion of the rib is of uniform height, the end portions 40 taper in height down to the top surface of the flange, so that no shoulder will be formed by the rib at its ends when the end portions of the flange are pressed down on the heel part of the innersole or tuck.

45 While the form of rib shown is considered the most desirable for all practical purposes, the formation may be somewhat varied without departing from my invention.

I claim:

1. A shoe counter having an inwardly projecting bottom flange, and having a rib on the upper or inner side of said flange adjacent the inner surface of the sides of the counter, to support the edge portion of the flange out of contact with 5 the heel part to which it is applied.

2. A shoe counter having an inwardly projecting bottom flange and having a rib on the upper or inner side of said flange in proximity to the inner surface of the sides of the counter, said 10 rib extending outwardly about the sides and back thereof approximately to the breast line of the heel to be applied thereto.

3. A shoe counter having an inwardly projecting bottom flange, said flange having a rib on its 15 upper or inner side molded integrally therewith and disposed adjacent the inner surface of the sides of the counter.

4. A shoe counter having an inwardly projecting bottom flange, and having a transversely convex rib formed on the upper or inner side of said flange in proximity to the inner surface of the sides of the counter and extending continuously from a point adjacent the breast line at one side about the back of the counter to a corresponding 25 point at the opposite side.

5. A shoe counter having an inwardly projecting bottom flange formed to taper to a sharp edge, and having an integrally molded rib formed on the inner or upper side of said flange in proximity 30 to the inner surface of the sides of the counter, said rib extending continuously for the entire edge portion of the heel seat of the shoe, to support the tapering edge portion of the flange out of contact with the heel part to which it is to 35 be secured.

6. A shoe counter having an inwardly projecting bottom flange, and having a rib on the upper or inner side of said flange adjacent the inner surface of the sides of the counter, said rib extending from a point adjacent the heel breast line at one side about the sides and back portions 40 of the counter to a point adjacent the breast line at the other side, the intermediate portion of said rib being of approximately uniform height and the end portions thereof being tapered in height 45 to the surface of the flange.

CHARLES A. THURSTON.
